[57] CLAIM

The ornamental design for a can, as shown and described.

DESCRIPTION

FIG. 1 is a side elevation of a can showing my new design, the appearance from all sides being the same; FIG. 2 is a top and bottom plan view of FIG. 1 and a top plan view of FIG. 4;

FIG. 3 is an enlarged partial cross-section taken on line 3—3 of FIG. 1;

FIG. 4 is a side elevation of an alternate embodiment of the can, the appearance from all sides being the same;

FIG. 5 is a bottom plan view of FIG. 4; and

FIG. 6 is an enlarged partial cross-section taken on line 6—6 of FIG. 4.

FIG. 1

FIG. 2

FIG. 3
